CLOTHES HANGER

Robert Clausen, Elizabeth, N. J.

Application April 5, 1950, Serial No. 154,153

3 Claims. (Cl. 223—88)

1

This invention deals with a hanger for clothes and, more particularly, to a hanger having movable, lockable spreaders of unique design, sliding on a toothed cross-piece for holding up trousers, skirts, and the like.

Many clothes hangers have been disclosed in the prior art. Some of them disclose a ratchet arrangement on a cross-piece for keeping apart spreading elements on which may be mounted trousers, skirts, etc. These devices have been found to be complicated and unadaptable to conventional bow-type hangers which the public is accustomed to use. Also, they require springs and intricate machining, thus making them highly impractical for commercial use.

The present invention involves a simple spreading mechanism operating on a toggle principle and requiring no springs or ratchets for satisfactory operation. The invention may be more readily understood by reference to the drawing in which Figure 1 is a front view of a preferred embodiment of the invention. A cross-sectional end view taken along II—II of Figure 1 is presented in Figure 2 while Figure 3 is a front view, partly in cross section, of one of the slidable, lockable spreading devices which engage the cross-piece of the hanger taken along III—III of Figure 2. Similar numerals refer to similar parts in the various figures.

Referring again to the drawing, numerals 1 and 2 represent the bent upper bow portions of the hanger, preferably made of flat or round metal wire, at the juncture of which is attached hook 3 which is riveted thereto by rivet 4. The lower portion of hook 3 may be provided with upwardly directed hook 5 on which some clothes may be hung.

The lower portions 9 of the bow portions are riveted by means of rivets 8 to the ends of cross-piece 6 which is preferably a flat strip of metal having a serrated lower edge 7 on which are engaged sliding members 10. These sliding members comprise a sleeve 10 surrounding the upper and side portions of cross-piece 6. The lower portions of sleeve 10 extend from each side as members 16, and then terminate downwardly as members 11 which act as spreaders and hold up trousers, skirts and the like.

Soldered or welded or otherwise fastened to the underside of extending members 16 is plate 17 which terminates with a downwardly and then upwardly directed projection 14, the tip of which acts as a pawl in the serrations 7 to engage same and prevent movement of sliding member 10, together with the complete slide assembly. Down-

2

wardly directed portion 18 is provided to keep releasing lever 13 on sleeve 10 and prevent its sliding off. Lever 13 is fitted over sleeve 10 with sufficient clearance to enable movement to the right or left to a slight degree.

Sleeve 10 is also provided with longitudinal clearance so as to enable tilting thereof when lever 13 is moved to the right, which action disengages projection 14 from serrations 7, thereby 10 unlocking sleeve 10 and allowing it to slide to the right. Serrations 7 are rounded off so that they do not catch the clothing and cause possible tearing thereof. The sleeve on the right is similar to the one on the left, but the parts are oppositely 15 disposed so as to enable locking and disengaging in a direction opposite to that of the left hand sleeve 10. The outermost edges of spreading members 11 are preferably indented so as to enable better gripping of the trousers, skirt, or the like.

In operation, the upper portion of the skirt or cuff portions of the trousers are slipped over spreading members 11 and members 11 are then 20 spread apart from each other with the thumbs until the skirt or cuffs are tightly stretched, and upon release of the thumbs, the skirt or trousers will remain on the hanger without any tendency 25 to slip off. The coat may then be placed on bow portions 1 and 2 and the hanger hung up by means of hook 3.

If the trousers or skirts are to be removed from the hangers, levers 13 are pushed towards each other with the thumbs, which action causes a 30 tilting of sleeves 10 by a sort of toggle action, thereby disengaging projection 14 from serrations 7, and causing the sleeves to slide toward each other, thereby releasing the skirt or trousers.

It is apparent, from the foregoing description, that the sleeve assembly is a simple mechanism 35 employing no springs or other flexing member which is apt to break or which requires considerable assembly time during manufacture.

I claim:

1. In a clothes hanger having an upper bow portion carrying a centrally disposed hook and a cross-piece connecting the ends of the bow, the improvement comprising serrations on the lower edge of said cross-piece, two oppositely disposed sleeve assemblies sliding on said cross-piece, each assembly comprising a sleeve disposed around said cross-piece and loosely enough longitudinally to enable tilting one end thereof in the vertical plane, at least one downwardly directed projection from the base of said sleeve to act as engaging and holding members for clothes to be held,

a laterally emerging projection from the end of said sleeve base directed upwardly to engage said serrations, and a lever projecting from the top of said sleeve to enable tilting of said sleeve to disengage said latter projection.

2. A clothes hanger according to claim 1 in which the projection from the base of the sleeve is directed downwardly and upwardly and the lever has a lower portion surrounding the sleeve

loosely longitudinally and disposed behind the downwardly projecting portion of said projection.

3. A clothes hanger according to claim 1 in which the sleeve has two parallel downwardly directed projections.

ROBERT CLAUSEN.
